(57) **CLAIM**

We claim the ornamental design for wrench for modular drilling tools, as shown and described.

DESCRIPTION

FIG. 1 is an isometric view from above of a wrench for modular drilling tools showing our new design;

FIG. 2 is a top plan view of the wrench of FIG. 1;

FIG. 3 is a bottom plan view of the wrench of FIG. 1; and,
FIG. 4 is a left side view of the wrench of FIG. 1, the right side
view being identical to the left side view.

1 Claim, 4 Drawing Sheets
